UNITED STATES PATENT OFFICE.

CHARLES E. SCRIBNER, OF CHICAGO, ILLINOIS, ASSIGNOR, BY MESNE ASSIGNMENTS, TO THE WESTERN ELECTRIC COMPANY, OF SAME PLACE.

ANNUNCIATOR-SWITCH AND TELEPHONE-CIRCUIT.

SPECIFICATION forming part of Letters Patent No. 293,197, dated February 5, 1884.

Application filed December 12, 1881. (No model.)

To all whom it may concern:

Be it known that I, CHARLES E. SCRIBNER, of Chicago, Illinois, have discovered a certain new and useful Improvement in Shutter-Switches and Telephone-Circuits, of which the following is a full, clear, concise, and exact description.

My invention is designed for use where several telephone-lines are grouped at their outer ends by a common line and connected at the central office with the common ground-wire of the listening operator; and it consists of switching devices placed at the subscribers' stations and operated by a battery from the central office.

In the drawings, Figure 1, I have shown four subscribers' stations, Nos. 1, 2, 3, and 4, grouped together by the common outer line, and connected at the central office, in the usual way, with the listening operator's outfit A. At station No. 1 I have shown a subscriber's outfit in detail, as combined with my switching device. The bell only is shown at stations Nos. 2, 3, and 4. The line of any given station is connected directly from its switch at the central office to the switch-lever of its station. Thus line *a* of station No. 1 is connected from switch *b* at the central office to lever *c* at station No. 1. When the telephone is not in use, the circuit passes from the lever, as shown, through the bell, and thence, as indicated by the dotted lines, through the shutter *d* of my switching device to the common outer line, *e*. On connecting the battery to line by inserting the plug *f* in the switch, line *a* is cut off from the listening operator's ground-line, and the first impulse of the battery moves the armature *g*, and the shutter *d* falls, making contact with the ground-point, as shown at station No. 1. The subscriber's individual line at any given station may thus be cut off from the grouping-line and connected automatically to ground, as shown at station No. 1.

My switching device, as thus described, is of great advantage when trouble is found to exist upon any line of a group, since the line may be disconnected from the rest of the group by the attendant at the central office. Heretofore it has sometimes been necessary to disconnect the whole group on account of trouble

upon a single line. In case of a cross, the current from the interfering line will immediately throw down the shutter of the switching device, so that the trouble will affect only the line that is in the cross.

In Fig. 2 I have shown a modification of my switching device upon the call-box in which the annunciator-drop is operated by the armature of the bell, instead of by the armature of a special magnet, as shown at station No. 1, Fig. 1. The lever shown in Fig. 2, which holds the shutter of the annunciator, is provided with a slot at its upper end. The vibrating hammer-rod passes through this slot. When the hammer-rod begins to vibrate, its motion is communicated to the lever, and as any motion of the lever releases the shutter falls as the bell begins to ring.

In Fig. 3, Sheet 2, I have shown the shutter *m* placed on the telephone-box just above the lever *n* of my automatic switch for telephones, described more particularly in Letters Patent No. 248,671 of October 25, 1881. The telephone-line *a'* is connected to the switch-lever, and its circuit may be traced from the lever *n*, through the metallic wedge *p*, to the metallic pin *r*, which is insulated from the frame of the switch, as shown. From thence the circuit of the telephone-line passes to the magnets of the bell, (not shown in Fig. 3,) and thence to the shutter *m* by line *s*, and thence to the armature *g'*, and thence to the special shutter-magnet (not shown in Fig. 3) to the common outer line. When the shutter first falls, it takes the position indicated by the dotted lines, its lower point just resting upon the point *o* of the insulated catch. On withdrawing the metallic wedge or ring *p* of the telephone from the switch the position of the lever is changed and the shutter falls into the notch *q*. The subscriber is thus compelled to replace the shutter before he can hang up the telephone.

I claim—

1. The combination of a group of telephone-lines with any usual central office and subscribers' outfits, with switching devices, one in the circuit of each line between the bell-magnet and common outer line, whereby any

line may be separated from the group and connected to ground, as and for the purpose set forth.

2. The combination of the annunciator-shutter with the contact piece or catch and the lever of the automatic switch, whereby the subscriber is compelled to replace the shutter before hanging the telephone on the switch.

3. The combination, with the switch at a

subscriber's station, of the shutter of an annunciator, adapted to be operated by current sent from the central office, and means whereby the subscriber must replace said shutter after a call before hanging up the telephone.

CHARLES E. SCRIBNER.
